CLAIM

The ornamental design for an air operated vehicle lifting jack, as shown and described.

DESCRIPTION

FIG. 1 is a top and side perspective view of the air operated vehicle lifting jack showing my new design;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof;

FIG. 7 is a bottom plan view thereof; and,

FIG. 8 is a perspective view showing the jack in combination with an air supply system.

The air supply system shown in FIG. 8 forms no part of the claimed invention.

FIG.1

FIG. 5

FIG. 4

FIG. 3

FIG. 2

FIG. 7

FIG. 6

FIG. 8
